DESIGN FOR A SETTEE

Salvatore Bevelacqua, New York, N. Y., assignor to The McKay Company, Pittsburgh, Pa., a corporation of Pennsylvania

Application November 21, 1935, Serial No. 59,681

Term of patent 7 years

To all whom it may concern:

Be it known that I, Salvatore Bevelacqua, a citizen of the United States, residing at New York, in the county of Manhattan, State of New York, have invented a new, original, and ornamental Design for a Settee, of which the following is a specification, reference being had to the accompanying drawing, forming a part thereof.

I claim:

The ornamental design for a settee, as shown.
SALVATORE BEVELACQUA.
